United States Patent Office.

ALONZO HEBBARD, OF NEW YORK, N. Y.

Design No. 2,664, dated June 4, 1867.

DESIGN FOR A SPOON OR FORK-HANDLE.

The Schedule referred to in these Letters Patent and making part of the same.

TO ALL WHOM IT MAY CONCERN:

Be it known that I, ALONZO HEBBARD, of the city, county, and State of New York, have invented or produced a new and original Design for the Handles of Spoons, Forks, and other articles of table cutlery, of which the following is a full, clear, and exact description of the same, reference being had to the accompanying drawings, making a part of this specification, the same letters of reference, wherever they occur, referring to like parts.

Figure 1 is a perspective view of the handle, showing in dotted outlines the blade of a spoon attached thereto.

Letter A represents an inverted six-sided truncated cone forming the head of the handle, the base of which is slightly rounded upwards, around the neck of which is a disk, b, having a milled edge, and surmounted by a spherical knob, c, to complete the upper end of the handle attached to its lower end, or the apex of the conical figure is a hexagonal stem, d, having on it, just below the apex of the conical figure, a second disk, e, with a milled edge, and near its junction with the blade of the fork or spoon (as the case may be) a collar, f, of corresponding number of sides with that of the stem, but of slightly increased diameter.

It will be obvious that the design will be enlarged or diminished in size according to its adaptation to dinner, tea, dessert, or other articles of table cutlery to which it may be applied.

Having now described my invention of a new design for the handles of spoons, forks, and other articles of table cutlery, I will proceed to set forth what I claim, and desire to secure by Letters of the United States.

I claim the design hereinbefore set forth and described for the handles of spoons, forks, and other articles of table cutlery.

Witnesses:

J. H. MUNSON,
C. L. BARRITT.

ALONZO HEBBARD.
